[57] **CLAIM**

The ornamental design for “wall mounted faucet”, as shown and described.

DESCRIPTION

FIG. 1 is a perspective view of wall mounted faucet showing my new design.

FIG. 2 is a front view thereof;

FIG. 3 is a rear view thereof;

FIG. 4 is a left side view thereof, the right side is identical;

FIG. 5 is a top view thereof; and

FIG. 6 is a bottom view thereof.

FIG. 7 is a perspective view thereof with a section line indicated; and,

FIG. 8 is a cross-sectional view taken along line 8—8 of FIG. 7.

The broken line showing is for illustrative purposes only and forms no part of the claimed design.
